UNITED STATES PATENT OFFICE.

JOSEPH F. DEMARCHI, OF EAST ORANGE, NEW JERSEY.

MACHINE-TOOL.

1,246,245.

Specification of Letters Patent.

Patented Nov. 13, 1917.

Application filed June 28, 1916. Serial No. 106,328.

To all whom it may concern:

Be it known that JOSEPH F. DEMARCHI, a citizen of the United States, and resident of East Orange, Essex county, New Jersey, has 5 invented certain new and useful Improvements in Machine-Tools, of which the following is a specification.

This invention relates to machine tools, such as taps, reamers, or the like, adapted 10 to be used as finishing tools.

The invention has for an object the provision of an adjustable tool of this type which is not only adapted for reaming or tapping holes of different sizes with the same 15 tool but which may also be used to operate in an opening of smaller diameter at the point of insertion of the tool than at the point where the tool is to operate. This function is accomplished by means of the 20 novel features of construction which will be described hereinafter.

A further object is to provide a simple construction for an expanding tool of this type.

For further comprehension of the invention, and of the objects and advantages thereof, reference will be had to the following description taken in connection with the accompanying drawings, and to the appended 25 claims in which the novel features of the invention are more particularly set forth.

In the accompanying drawings illustrating an embodiment of my invention:

Figure 1 is a longitudinal elevation of a 30 machine tool embodying the invention.

Fig. 2 is a longitudinal section thereof.

Fig. 3 is a transverse section on the line 3—3 of Fig. 2.

Fig. 4 is a similar view of the line 4—4 of Fig. 2.

Fig. 5 is an end view thereof.

Fig. 6 is a detail view in longitudinal elevation of the adjusting member.

As here shown, my improved machine tool 45 comprises a cylindrical casing 1, the forward portion of which is formed with a series of elongated radial slots 3. Mounted in these slots to slide radially in the casing are reamer bars or cutting members 4 having 50 cutting edges 5 formed thereon. Adjacent the forward end of the casing the slots 3 extend only partially through the wall of the casing in a radial direction but entirely through in a longitudinal direction, as indicated at 3', while the reamer or cutter bars

have their outer portions, on which are formed the cutting edges 5, longer than their inner portions and extending through the forward ends of the slots 3 substantially flush with the forward end of the casing 1. 60 This arrangement permits the tool to be used to ream out an opening to the bottom wall thereof.

These reamer bars 4 have angular grooves 6 cut longitudinally on one face thereof to 65 provide dove-tailed portions 7 on the bars 4, which engage in similarly formed slots 8 in an adjusting member 9, which is slidably positioned in the casing 1, and, as shown most clearly in Figs. 4 and 5, fits snugly, or 70 closely, in the interior of the casing.

This adjusting member 9 may be inserted through the forward or right hand end, as shown in Figs. 1 and 2, of the casing 1, a removable cap or plug 10 being screwed into 75 said end and serving to limit movement of the adjusting member 9 in one direction, movement in the opposite direction being limited by co-acting shoulders, indicated at 80 11, formed on the adjusting member 9 and interior wall of the casing. The slots 8 in the adjusting member 9 converge inwardly or taper toward the front or right hand end, as shown in Figs. 1 and 2, and the dove-tail portions 7 of the reamer bars are correspondingly inclined, as clearly shown in 85 Fig. 2. The operating portions of the adjusting member 9, that is the portions represented by the bottom faces of the slots 8, are thus of wedge shape. In the face view the 90 slots 8 will have the appearance of widening toward the rear, as shown in Fig. 6, by reason of the slots being cut on a taper, while the sides are parallel.

It will be apparent that when the adjusting member 9 is moved longitudinally in the casing 1, the inclined surface of the slots and the reamer bars will cause the latter to be forced inwardly or outwardly in the slots 3 to contract or expand the 100 reamer, according to the direction of movement of the rod 9, these inclined surfaces constituting in effect cams. As will be clearly apparent from Fig. 2 of the drawing, an inwardly facing transverse wall is 105 formed adjacent the forward end of the casing by the plug 10, this wall engaging the forward ends of the inner portions 7 of the cutter bars 4 to prevent forward displacement thereof while the outer portions 110

project forwardly over this wall 10 to the desired point to enable the same to cut to the bottom of a hole.

The means which I have shown for moving the adjusting member 9 longitudinally in the casing 1 comprises a screw 15 threaded into the left hand end of the adjusting member 9 which extends rearwardly of the cutting bars, the screw 15 being held against longitudinal movement by any suitable means, as the pin 16 engaging an annular groove 17 in the screw. The screw 15 may also have a flange 18 thereon which bears against a shoulder 19 on the casing to take the end thrust. I have here shown a squared head 20 at the rear end of the casing 1, while the screw 15 may have a square socket 21 formed therein for insertion of a key to rotate the screw 15. It will be noted that the engagement of the reamer bars 4 in the slots 8 prevents rotation of the adjusting member 9.

The method of use of my improved tool will be apparent from the above description, but it may be added that when the tool is to be used on a boring which may have a smaller diameter at the point of insertion of the reamer than at the point where the cutting bars are to work the reamer is inserted in the opening and the bars expanded after inserting, before mounting the reamer in the chuck of the lathe or other machine. Similarly, to remove the reamer the chuck is removed and the reamer bars contracted to permit the tool to be withdrawn through the smaller opening.

In contracting the bars 4, the dove-tailed portions 7 engaged in the corresponding slots 8 in the adjusting member 9 operate positively to draw the bars inwardly. This feature is important in devices of this nature, as it is necessary for the bars 4 to fit snugly in the slots.

It will be apparent that various changes and modifications might be made in the construction as illustrated without departing from the scope of the appended claims.

What I claim is:

1. A machine tool comprising a cylindrical casing having a plurality of radial slots therein, cutter bars positioned in said slots, and an adjusting member fitting snugly

within the cylindrical casing and adapted to engage the inner portions of said cutter bars to adjust the position of the same radially in said slots, the said casing presenting an inwardly facing transverse wall adjacent its forward end adapted to engage the inner portions of the forward ends of the cutter bars to prevent forward displacement of the latter, said cutter bars having their outer portions projecting forwardly beyond the said inner portions over the said transverse wall.

2. A machine tool comprising a cylindrical casing having a plurality of radial slots therein extending longitudinally through to the forward end of the casing, said slots extending only partially through the casing in a radial direction adjacent the forward end thereof, cutter bars positioned in said slots, said cutter bars having their outer portions extending forwardly beyond their inner portions through the last mentioned portions of the said slots, and an adjusting member fitting snugly within said casing and slideable therein and adapted to engage the inner faces of the cutter bars to adjust the latter radially in the said slots.

3. A machine tool comprising a cylindrical casing having a plurality of radial slots therein, cutter bars positioned in said slots, and means adapted to engage the inner portions of said cutter bars to adjust the position of the same radially in said slots, said cutter bars having their cutting portions longer than said inner portions and extending outwardly substantially flush with the forward end of the casing.

4. A machine tool comprising a cylindrical casing having a plurality of radial slots extending through the wall thereof, said slots adjacent the forward end of the casing extending only partially through said wall radially but entirely through in a longitudinal direction, cutter bars positioned in said slots, said cutter bars having portions extending through the forward end of said slots substantially flush with the forward end of said casing, and means for adjusting said cutter bars radially in said slots.

Signed at the city, county and State of New York, this 22d day of June, 1916.

JOSEPH F. DEMARCHI.
